REMOVABLE PLUG FOR DRILLING STRINGS

Horace Vivian Steadman and Ellis E. Davis, Tulsa, Okla., assignors to Shell Development Company, San Francisco, Calif., a corporation of Delaware

Application June 24, 1941, Serial No. 399,476

11 Claims. (Cl. 255—72)

The present invention relates to the drilling of wells and pertains more particularly to drill string plugs or seals, which may be suitably placed in and removed from the drill string without the necessity of removing or raising the drilling equipment from the borehole.

In drilling wells by the rotary method, it is essential that a high ascending velocity of the drilling mud be maintained in order to remove the drill cuttings from the well. A high ascending mud velocity becomes increasingly important when the drill is making hole more rapidly, when the cuttings become larger or denser, and especially when effecting the so-called well-cleaning operations preparatory to completing the well. For the purpose of increasing the ascending velocity of the mud fluid without overtaxing the pumping equipment, it is generally the practice to apply reverse circulation, whereby the mud fluid is pumped down the annular space between the drill string and the casing or borehole and then passes up through the drill string. Due to the smaller space within the drill string the fluid passes upwards at a greater rate, thereby increasing the fluid carrying power for cuttings. When employing this method of mud circulation, it is usually necessary to enlarge the water courses through the drill bit.

As mentioned above, it is generally desirable to wash the walls of the section of the borehole when this section of the bore-hole is thought to be the producing zone, and it is expected to complete the well and to put it on production. Heretofore, the washing was accomplished by replacing the drill bit having enlarged water courses with a plug or the like having small lateral jetting holes and then pumping the circulation medium down through the drill string and out through the jetting holes while rising and lowering the drill string to subject all or normally only a part of the borehole to the jetting action. The detritus, which accumulates in the bottom of the borehole during jetting, is then removed by reverse circulation after reinstalling the drill bit. Frequently, and particularly after shooting a well with explosives, it is desirable to wash a section of the borehole several times and to remove the detritus washed down on the completion of each jetting. Since each change to replace the drill bit with the jetting tool or vice versa requires withdrawing the entire drill string from the hole, the procedure of jet-washing the borehole and removing the detritus several times is a time-consuming and therefore costly operation.

It is, therefore, an object of the present inven-

tion to provide means for eliminating the necessity of removing the drill string from the borehole while jet-washing the walls and removing the detritus accumulated after each washing.

It is another object to provide drill string plugging means insertable into and removable from said drill string by fluid circulation through said string and capable of closing off the watercourses through the drill bit while permitting fluid flow from the drill string out through jetting holes positioned a relatively short distance above the drill bit.

It is a further object to provide a simple, inexpensive, and efficient well drill string plugging device, which may be passed down the drill string to the desired position by means of fluid circulation.

It is still another object to provide means for lowering and raising various tools in a string of well pipe or the like, which means is actuated into and out of position within said pipe string by fluid circulation through said string.

With the above and other objects in view, the invention has particular relation to certain novel features of construction, operation, and arrangement of parts, an example of which is given in this specification and illustration in the accompanying drawings, wherein:

Figure I is a view, partly in section, of a preferred embodiment of the present device as positioned in a well drill string;

Figure II is a view similar to that of Figure I, showing the collapsed position of the present device in a well drill string during jet-washing of the borehole walls;

Figure III is a view similar to that of Figures I and II, showing the position of the device just as flow is reversed to remove the device from the well drill string;

Figure IV is an enlarged longitudinal cross-sectional view of the present device;

Figure V is an elevation of the present device as attached to a casing spear for plugging the lower end of a drill string; and

Figure VI is a view, partly in elevation, showing the use of the present invention in combination with instruments for taking well cores.

Referring to Figure IV of the drawings, a preferred embodiment of the plugging device comprises a mandrel or stem 1 having threaded ends 2 and 3, a lower hydraulic cup 5 coaxially and rigidly attached adjacent one end of said mandrel 1, and an upper hydraulic cup 6 coaxially and slidably mounted on said mandrel 1. The cups 5 and 6 may be single, as shown, or mul-

triple units and are adapted to withstand the fluid pressure imposed upon them. The lower hydraulic cup 5 is upwardly flared; that is, it has a concave upper face 7, allowing pressure applied thereabove to expand it. The upper cup 6 has a concave lower face 8, opposing the face 7 of the lower cup 5. The cups may be of any suitable design, and are made of elastic or flexible material such as, preferably, natural or synthetic rubber, or other suitable materials, for example, canvas, rubberized canvas, etc. The cups 5 and 6 are preferably reinforced by protective metal rings 10 within the axial bores 11 of said cups, and by a plurality of wires 12 attached at one end to said rings 10 and passing therefrom to and along or inbedded in the outer or convex surface of the cups. The wires 12 extend beyond the open or concave end of the cups and are drawn down to and held by a restraining ring 14, which is of smaller diameter than that of the outside diameter of the cups. The wires 12 are preferably formed of suitable resilient material, such as spring steel or the like, so that the cups 5 and 6 are normally held in a non-expanded or collapsed position. The cups 5 and 6 may be further reinforced by means of annular thimbles or rings 20 having tapered faces 21 complementing and abutting the convex faces of said cups.

The lower cup 5 is rigidly held in place on the lower end of the mandrel 1 by means of a plug nut 25 screwed onto the threaded end 3 of the mandrel and abutting the annular thimble 20 on one side of the cup 5 and by means of a tubular follower 26 abutting the cup 5 and reinforcing ring 10 on the other side of the cup 5. The plug nut 25 is suitably prevented from loosening by means of, for example, lock screws 30. Similar lock screws 31 or the like prevent movement of the tubular follower 26.

A nut 35 and lock nut 36 are screwed onto the other threaded end 2 of the mandrel 1 and constitute stop means against which the movable cup 6 is preferably normally held by suitable resilient means, such as a coil spring 40 surrounding the mandrel and acting between the stationary tubular follower 26 and a slidable tubular follower 41 similar to follower 26. For some operations for which the present device is adapted, the spring 40 or other resilient means is not absolutely necessary. When the resilient means is omitted as for some purposes, it is preferable that some suitable spacer means be provided between the cups to stop movement of said slidable cup 6 toward the fixed cup 5 at a predetermined distance away from said fixed cup so that the cups will be prevented from coming together in such a way as to prevent fluid from acting against the concave faces of the cups to expand them. In the preferred embodiment described above, the followers 26 and 41, which project out from the concave faces of the cups, readily serve as stop means for this purpose. If desired, both cups 5 and 6 may be fixedly attached adjacent the respective ends of the mandrel 1; however, for most purposes, greater efficiency and facility of action of the device is obtained when some such resilient means is provided. For example, the use of said spring or the like will materially aid in obtaining better service from the top cup 6, since said cup will then not be subject to hydraulic washing caused by restricting passage of the fluid between the cup's outer surface and the walls of the tubing.

Referring to Figures I, II and III, the operation of the above-described device, when used

in connection with jet-washing the borehole and removing the detritus, will be described hereinbelow in relation to a well borehole 58, having depending thereinto a drill pipe string 51, to the lower end of which is attached a drill bit 53 having a water course or courses 54 passing therethrough. The lower section of the drill pipe string 51 is provided with lateral jetting holes 55 at a relatively short distance above the lower end of said string, and, preferably, with a non-flow-restricting stop means, such as a pin 57 bridging the bore of the string closely adjacent the lower end thereof. If desired, a special tube or pipe containing the jetting holes 55 and the stop pin 57 may be inserted between the lower end of the drill string 51 and drill bit 53. Likewise, the shank of the drill bit 53 may serve as stop means instead of any special means, if desired.

When it is desired to jet-wash the walls of the borehole after drilling with reverse circulation, the path of the circulation medium is directed so that the fluid passes in the regular manner down through the drill string 51 out through the water courses 54 in the drill bit and up to the surface through the annular space between the drill string 51 and the walls of the borehole 58.

The present plugging device is then introduced into the drill string and is forced down within the drill string by the pressure of the circulation medium above it acting upon the lower and stationary hydraulic cup 5, which is expanded against the walls of the drill string by said pressure, as shown in Figure I. The plugging device travels down through the drill string until the plug nut 25 on the lower end contacts the stop pin 57. At this point in the procedure, the spring 40 is still expanded and the upper cup 6 is positioned above the jetting holes or ports 55, as shown in Figure I. With a further increase in pressure of the circulation medium occurring when the device is stopped by the pin 57, the upper slidable cup 6 is forced downwards against the action of the spring 40, thereby exposing the jetting ports 55 to the full force of the pressure of the circulation medium, as shown in Figure II. With the water courses 54 in the drill bit closed by the expanded lower cup 5 and with the jetting ports 55 exposed, the circulation medium flows at a high rate out through the small jetting ports 55 and impinges against the walls of the borehole. The jet-washing of the desired section of the borehole is carried out in this manner while raising and lowering the drill string through the desired distance.

On completing a jet-washing, circulation of the fluid is reversed, whereby the lower cup 5 collapses due to resilient action of the cup itself and of the spring wires 12, and the upper cup 6 rises to the upper limit of travel against the stop nut 35 by the action of the coil spring 40. Due to the pressure of circulation medium therebelow, cup 6 expands into sealing engagement with the drill string walls. On continued flow of circulation medium through the water courses 54 and the jetting ports 55 into the drill string 51 below the cup 6 the plugging device travels upward to the surface of well, where it may be removed from the drill string. Reverse circulation may then be continued to remove the detritus which has accumulated in the bottom of the borehole during the jet-washing.

Drilling may then be resumed, or by again inserting and removing the plugging device the borehole walls may be jet-washed and the detritus removed any number of times before

resuming drilling without at any time having to remove the drill pipe string from the borehole. It may be readily seen that according to the present invention the considerable time necessary for removing and replacing the drill string after and before each operation is obviated.

Further, the present plugging device may be used in combination with various well tools for positioning said tools in a drill pipe string or tubing string and for removing said tools therefrom. Referring to Figure V, one highly advantageous combination is with a casing spear or similar inside gripping means. In the event that the formation pressures become sufficient to displace the fluid from the well, thereby causing a disastrous situation commonly known as a "blow out", it becomes necessary to plug the drilling string in order to avoid hazard to the well, personnel, and farm land. To prevent such an occurrence, there may be inserted into the drill string and forced downward therethrough the combination of the plugging device of the present invention with means for gripping the walls of the drill string, which means move into wall-gripping engagement upon upward movement thereof. For this purpose, the plugging device may be inverted, as shown, and the plug nut 25 replaced by any suitable inside wall-gripping means, such as, for example, a casing spear generally designated as 10. The spear 10 may, for example, comprise a mandrel 11 having lateral recesses 12 provided with downwardly diverging tapered faces 13, as shown in Figure V. Tapered slips 14 having horizontal teeth 15 on their outer vertical sides are adapted to slide downwardly and outwardly on the tapered faces 13 into wall-gripping engagement upon upward movement of the mandrel 11. Said slips 14 are held in slidable engagement with said tapered faces 13 by means of engagement of a key 16 and key way on each face 13 and slip 14, respectively, as shown in Figure V, or vice versa. It is often advisable when so using the plugging device to substitute, as shown in Figure V, a tubular member 18 of rubber or like material for the spring 40 to assist the upper cup in sealing off the drill string as described below. If desired, instead of gripping means attached above, as shown, or below the plugging device, as just described, a dog-mechanism or the like may be carried between the cups 5 and 6.

To shut off the drill string near its bottom end or at any desired position, the above-described combination is inserted into the drill string and fluid pumped thereinto above the plugging device, whereby the fluid pressure against the cup 6 forces the combination assembly down to the desired position. By metering the amount of fluid introduced into the drill string after the device is inserted, the position of the device is accurately known. When the device reaches the desired position, the pressure on the fluid above the device is released, allowing the full well pressure to act against the cup 5. The cup 5 is thereby expanded into sealing engagement with the walls of the drill string and caused to move slightly upward. The upward movement of the mandrel 11 carried by the plugging device causes the toothed slips 14 to be moved outwardly along the tapered faces 13 of the recesses 12 into engagement with the walls of the drill string. The plugging device is thus held in the desired position within the drill string and the sealing action of the cup 5 prevents upward flow of well fluid through the drill string, thereby bringing the well under control.

The tubular member 18, such as a rubber sleeve commonly known as "a pack-off rubber," aids in effecting a stronger seal against the high pressure differential across the plugging device. By means of this combination of the plugging device with a casing spear, the drill string can be removed from a flowing well while maintaining said well under control.

As a further example of one of the many uses of the present invention, the plugging device may be used in connection with means for obtaining cores from a well. With the present device a core barrel may be removed from the well, the cores emptied from the core barrel, and the core barrel reinserted into core-taking position without removing the drill string from the well. For this purpose, as shown in Figure VI, the bottom plug nut 25 of the plugging device is replaced by a core barrel 90 attached to the lower end of mandrel 1 of the plugging device by means of a coupling 91 containing, if desired, an upwardly-opening ball valve 92 or the like, which provides a one-way passage for fluid flow from the inside of the core barrel 90 to the annular space outside the core barrel. The lower end of the core barrel 90 is provided with tapered face 93 having a packing insert 94 of rubber, leather or the like. Within the core barrel 90 adjacent the lower end thereof are any suitable core catchers 95. During core taking, as shown in Figure VI, the tapered face 93 on the lower end of the core barrel 90 seats in a complementary tapered internal shoulder 96 of the core bit head 97, which is provided with water courses 98 to allow circulation of drilling fluid therethrough. The bit head 97 is attached to the lower end of a tubular member 100, which is in turn attached to the lower end of the drill string 51. The tubular member 100 has a thickened portion 102 disposed so that, when the assembly of the plugging device and the core barrel is properly positioned for core taking, the lower cup 5 is within the thickened portion 102. The thickened portion 102 is cut away to form vertical slots 103 allowing fluid to by-pass the lower cup 5.

With the assembled combination of the plugging device and core barrel 90 in core taking position, as shown in Figure VI, drilling fluid is circulated down through the drill string 51 past the upper cup 6 and through the slots 103 in the thickened portion 102 of the tubular member 100 past the lower cup 5 and thence down through the annular space 101 between the core barrel 90 and the tubular member 100 and out through the water courses 98 in the core bit head 97 into the borehole and up through the annular space between the tubular member 100 or drill string 51 and the bore hole 50. The pressure against the lower cup 5 of the fluid passing down past it holds the core barrel 90 in seated position in the drill bit head 97. Coring proceeds with fluid circulation in this manner until the core taken fills the core barrel 90. The core barrel 90 containing a core held therein by means of catchers 95 and the plugging device attached thereto is then removed from the tubular member 100 and drill string 51 by reversing the direction of fluid circulation. In addition to the imposition of fluid pressure against the lower extremity of the core barrel, the pressure of the fluid passing up through the tubular member 100 acts against the upper cup 6 and expands it against the walls thereof, whereby the plugging device and core barrel 90 attached thereto are forced upward to the surface by means of fluid circulation.

After removing the core barrel from the well and emptying the core therefrom, the assembly may be reinserted into the drill string 51 and forced down through drill string 51 by fluid pressure thereabove into position for taking another core.

Thus, it may be readily seen that the use of the plugging device in combination with a core barrel offers the outstanding advantage of taking an unlimited number of well cores without removing the drill string from the borehole after coring is started, thereby effecting a considerable saving of time and expense.

It will be readily understood that the drawings and description are illustrative only of preferred embodiments of the present invention and that various modifications may be readily made without departing from the scope of the invention, as defined in the appended claims. Thus, for example, the plugging device may be used to advantage in combination with various tools other than those indicated and, likewise, modifications may be made in the plugging device itself.

We claim as our invention:

1. A well pipe tool adapted to be moved within a well pipe by fluid circulation, said tool comprising a mandrel, and two opposed hydraulic cups coaxially mounted on said mandrel, one of said cups being rigidly fixed on said mandrel adjacent one end thereof, and the other cup being adapted for limited slidable motion on said mandrel.

2. A well pipe tool adapted to be moved within a well pipe by fluid circulation, said tool comprising a mandrel and two hydraulic cups coaxially mounted on said mandrel and having their concave faces directed toward each other, one of said cups being rigidly fixed on said mandrel adjacent one end thereof, and the other cup being adapted for limited slidable motion on said mandrel.

3. A well pipe tool adapted to pass to and from a desired position in a well pipe by fluid flow through said pipe, said tool comprising a mandrel, a hydraulic cup rigidly fixed coaxially on said mandrel adjacent one end thereof and having its concave side facing toward the other end of the mandrel, and a second hydraulic cup coaxially attached to said mandrel and adapted for limited slidable motion thereon, the concave side of said second cup facing the concave side of said fixed cup.

4. A well pipe tool adapted to pass to and from a desired position in a well pipe by fluid flow through said pipe, said tool comprising a mandrel, a hydraulic cup rigidly fixed coaxially on said mandrel adjacent one end thereof and having its concave side facing toward the other end of the mandrel, a second hydraulic cup slidable and coaxially attached to said mandrel, the concave side of said second cup facing the concave side of said fixed cup, and spacer means adapted to limit the movement of said slidable cup toward said fixed cup.

5. A well pipe tool adapted to pass to and from a desired position in a well pipe by fluid flow through said pipe, said device comprising a mandrel, a hydraulic cup rigidly fixed coaxially on said mandrel adjacent one end thereof and having its concave side facing toward the other end of the mandrel, and a second hydraulic cup coaxially attached to said mandrel and adapted for limited slidable motion thereon, the concave side of said second cup facing the concave side of said fixed cup, said cups being adapted to ex-

pand against the walls of the well pipe when fluid flow is directed against their concave sides.

6. A well pipe tool adapted to pass to and from a desired position in a well pipe by fluid flow through said pipe, said tool comprising a mandrel, a hydraulic cup rigidly fixed coaxially on said mandrel adjacent one end thereof and having its concave side facing toward the other end of the mandrel, a second hydraulic cup slidably and coaxially attached to said mandrel, the concave side of said second cup facing the concave side of said fixed cup, and resilient spacer means adapted to hold said slidable cup normally at a predetermined distance from said fixed cup.

15 7. A well pipe tool adapted to pass to and from a desired position in a well pipe by fluid flow through said pipe, said tool comprising a mandrel, a hydraulic cup rigidly fixed coaxially on said mandrel adjacent one end thereof and having its concave side facing toward the other end of the mandrel, a second hydraulic cup slidably and coaxially attached to said mandrel, the concave side of said second cup facing the concave side of said fixed cup, and resilient spacer means disposed between said cups and adapted to hold said slidable cup normally at a predetermined distance from said fixed cup.

20 8. A pressure shut-off device for well pipe strings, said device comprising a mandrel provided with gripping means adapted to engage the internal walls of said pipe upon upward movement of said mandrel, means to position said device within said pipe by a downward fluid flow, said means comprising an upwardly flaring hydraulic cup coaxially carried by said mandrel, and means for engaging said gripping means with the pipe walls by a reversal of said fluid flow, said means comprising a downwardly flaring hydraulic cup coaxially carried by said mandrel.

25 9. A pressure shut-off device for well pipe strings, said device comprising a mandrel provided with gripping means adapted to engage the internal walls of said pipe upon upward movement of said mandrel, means to position said device within said pipe by a downward fluid flow, said means comprising an upwardly flaring hydraulic cup coaxially carried by said mandrel, means for engaging said gripping means with the pipe walls by a reversal of said fluid flow, said means comprising a downwardly flaring hydraulic cup coaxially carried by said mandrel, one of said cups being fixedly attached to said mandrel and the other being adapted for limited slidable motion thereon, and a resilient spacer sleeve coaxially carried by said mandrel between said hydraulic cups, said sleeve being adapted to be deformed into contact with the pipe walls by a motion of said movable cup toward said fixed cup.

30 10. For use in coring operations in combination with a drill string having a core bit and an internal axially segmented restriction above said bit, a coring tool comprising a core barrel adapted to seat within said bit, a mandrel, valved means for rigidly affixing said mandrel above said barrel coaxially therewith, and means for seating said barrel within said bit and for removing it therefrom by fluid circulation, said means comprising an upwardly flaring hydraulic cup coaxially carried by said mandrel and adapted to register with said segmented restriction in the drill string when the core barrel is seated within the bit, a downwardly flaring hydraulic cup coaxially carried by said mandrel above said

first cup, one of said cups being fixedly attached to the mandrel and the other adapted for limited axial motion thereon, and resilient spacer means for normally maintaining said cups at a predetermined distance from each other.

11. In apparatus for completing oil and gas wells, the combination of a drill bit having a liquid circulation opening, a drill string supporting said bit, said drill string having relatively small lateral jet ports in its lower portion adjacent said bit, a mandrel having at its lower end an upwardly flaring hydraulic cup fixedly attached thereto and at its upper end a downwardly flaring hydraulic cup axially slidably on said mandrel towards said fixed cup, resilient

means spacing said cups on said mandrel, said mandrel being adapted to be pumped down the drill string by liquid circulation, stop means for arresting said mandrel adjacent the drill bit, whereby said lower cup is caused to close the bit opening and said upper cup is maintained above said lateral ports, means for slidably forcing said upper cup on said mandrel to a position below said ports by applying hydraulic pressure within the drill pipe, and means to remove said mandrel to the surface by reversing the direction of the liquid circulation.

HORACE VIVIAN STEADMAN.
ELLIS E. DAVIS.
